SETTABLE PRINTING MEANS IN
ACCOUNTING MACHINES

Eugene E. Murphy, Chicago, Ill.

Application March 19, 1947, Serial No. 735,703

21 Claims. (Cl. 101—90)

1

This invention relates to improvements in accounting machines or business machines, and relates particularly to an improved machine for simultaneously printing, by a single operation, a plurality of record entries which have been previously designated upon a master or control record card.

The present invention has application to numerous business transactions wherein multiple record maintenance is of importance, such as in the keeping of perpetual inventory systems, pay roll records, insurance records, pension systems, municipal records of many descriptions such as tax records and the like, and although the invention has applications too numerous to set forth herein, for purposes of illustration, its application to the maintenance of pay roll records will be described without, of course, intending to limit the use of the invention to this specific transaction, or to a transaction wherein this specific number of records are to be kept.

One of the important features of the present invention resides in a mechanism wherein the type of a printing frame is automatically set by a master or control printing card which type, by a single printing operation, can be made to print predetermined record data on a plurality of cards, record sheets, ledger sheets or the like.

Another important feature of the invention resides in the provision of a master or control card, which, having once been set to control a predetermined printing operation, can, if desired, be used as a record itself for future reference, or can, at the option of the operator, be reused, by resetting, to control further and different printing operations.

Briefly described, the present invention comprises a machine which carries a type frame having a plurality of type characters movable to and from a printing position, means for carrying record sheets interleaved with carbon paper at said printing position, a seat for positioning a master or control card in operative position with respect to the type frame to move said type to printing position and a pressure roller for pressing said record sheets and carbon papers into printing contact with the type disposed at the printing position.

Other objects and advantages of my invention will be apparent from the accompanying drawings and following detailed description.

In the drawings, Fig. 1 is a top plan view of a machine comprising the concepts of the present invention.

Fig. 2 is a sectional view taken on line 2—2

2

of Fig. 1 illustrating an adjustable stop for one of the record sheets employed in the machine.

Fig. 3 is a transverse sectional view taken on the line 3—3 of Fig. 1, looking in the direction of the arrows.

Fig. 4 is a longitudinal, sectional view taken on the line 4—4 of Fig. 1, looking in the direction of the arrows.

Fig. 13 is a detailed sectional view taken on the line 13—13 of Fig. 3 looking in the direction of the arrows.

Fig. 14 is an enlarged detailed view, parts being broken away and parts being shown in section, of the web moving mechanism employed in conjunction with the machine.

Fig. 15 is an enlarged sectional view illustrating the master card and printing frame in operative position, the view being taken along the line of type in printing position.

Fig. 16 is an enlarged sectional view illustrating the master card and printing frame in operative position, the view being taken at right angles to the line of printing position.

Fig. 17 is a view similar to that shown in Fig. 16 illustrating the type carrying frame and master card in inoperative position.

Fig. 18 is a fragmentary face view of a typical web-type record acted upon by the machine.

Fig. 19 is a face view of a check which may be acted upon by the machine.

Fig. 20 is a similar view of another record card which may be acted upon by the machine.

Fig. 21 is an enlarged sectional view illustrating the type carrying frame of a modification of the present invention, said view being taken along the line of printing.

Fig. 22 is a similar view taken substantially at right angles to view 21.

Fig. 23 is a fragmentary top plan view of the mechanism shown in Figs. 21 and 22.

Fig. 24 is a top plan view of a machine employing the type carrying frame illustrated in Figs. 21, 22 and 23.

Fig. 25 is a sectional view taken on the line 25—25 of Fig. 28, illustrating another modification of the present invention.

Fig. 26 is a transverse sectional view taken on the line 26—26 of Fig. 25.

Fig. 27 is a detailed sectional view taken on the line 27—27 of Fig. 26 illustrating an impression name plate which may be utilized with the device illustrated in Fig. 26.

Fig. 28 is a fragmentary top plan view illustrating the modified printing mechanism shown in Figs. 25 and 26.

Fig. 29 is an enlarged detailed view illustrating indexed indicia employed in conjunction with the racks utilized in the modification shown in Figs. 25, 26 and 28.

Fig. 30 is a front elevational view of a modified form of master or control card which may be employed in connection with the machine comprising the present invention.

Fig. 31 is a detailed sectional view taken on the line 31—31 of Fig. 30.

Fig. 32 is a fragmentary sectional view illustrating the card shown in Fig. 30 in operative position.

Referring in detail to the drawing, 1 indicates generally a machine comprising an embodiment of the present invention. The machine 1 comprises a frame having side walls 2 and 3 and end walls 4 and 5, and a top 6. The frame may be supported upon feet 7 which are secured by means of bolts or the like 8, to inturned flanges 9 of the side and end walls.

A roller 10 is journalled transversely upon the frame and is adapted to carry a web of carbon paper. For purposes of illustration, the web is shown as being wound upon the roller 10 as shown best at 13 in Fig. 6. The roller 10 is positioned adjacent the upper portion of the frame at its forward end and may comprise the supply roll. At the opposite end of the frame a similar roller 14 is journalled transversely upon the frame and is adapted to function as a take-up roll 15 for the carbon web 12. Intermediate the rollers 10 and 14 the carbon web 12 is carried across the upper portion of the top 6 of the frame. In order to conveniently rotate the rollers 10 and 14, knurled knobs 16 and 17 are secured to the respective ends of the rollers 10 and 14.

For purposes of illustrating the operation of the present invention, its use in conjunction with the preparation of pay roll records will be described. It is to be understood, of course, that the present invention has numerous applications and, hence, it is not intended that the illustrated operation be considered a limitation.

Referring particularly to Figs. 18, 19 and 20, embodiments of the essential documents comprising a pay roll record are shown. These documents comprise essentially a pay roll journal 18, an earnings record card 19 and a check 20.

In the maintenance of the pay roll system, the pay roll journal 18 may comprise a printed web wherein the names of the various employees appear, together with other pertinent data pertaining to those employees including the net pay received by the employees, the numbers of the checks issued, the gross pay of the employees, the hours worked, various pay roll deductions, etc. The pay roll journal essentially comprises a running account of all of the employees included in the particular system in question.

The earnings record card 19 also comprises an integral portion of the pay roll system and includes essentially pertinent pay roll data of an individual employee. A check 20 also comprises a portion of the pay roll records, said check in addition to having the normal information inscribed thereon in the main body of the check indicated by the numeral 21, may also carry a detachable stub 22 upon which may be inscribed the various pertinent data pertaining to deductions, gross pay, net pay and hours worked, the stub being submitted with the check proper to the employee as part of his personal record.

It can readily be seen that the data appearing on the pay roll journal is duplicated on the earnings record card and also on the check. It is desirable, of course, that this data, which frequently differs from pay period to pay period, be printed upon the three records simultaneously. In the machine comprising the present invention such operation can be conveniently performed.

It can readily be seen that other accounting procedures follow a somewhat similar pattern and the present invention will therefore find use in conjunction with the recording of any type of business transaction wherein a plurality of records are maintained containing duplicate data.

Referring particularly to Figs. 4 and 6, a roller 23 is journalled transversely in the frame of the machine and is conveniently positioned beneath the carbon web roller 14. The roller 23 is adapted to carry a roll of paper 24 from which a web 25 may be drawn, the web 25 may be carried through an aperture 26 provided in the top 6 of the machine and said web may be carried forwardly upon the top 6 to aperture 27 provided adjacent the opposite end of the machine. Said web may then be wound into a roll 28 which may be carried upon roller 29 journalled in the frame of the machine. The web 25 may comprise the pay roll journal 18, the roller 23 carrying a supply roll 24 and the roll 28 being the take-up roll. To have access to the rollers 23 and 29, the ends 5 and 4 respectively, may be provided with apertures formed by striking in a portion 30 and 31 of the respective ends.

In utilizing the present machine in the making of the pay roll records, the web 25 is positioned immediately above the upper surface of the top 6. Above said web, web 12 of carbon paper may be positioned with the coated side of the carbon paper facing the web 25. Above the web 12, the earnings record card 19 may be disposed and in turn a sheet 11 of carbon paper may be positioned above the earnings record card. The check 20 may then be positioned above the sheet 11. The means for printing the check will be hereinafter more fully described.

Referring particularly to Figs. 4, 6 and 8, 32 indicates a type carrying frame, hereinafter referred to as the type frame. The type frame 32 may comprise angle irons 33 which are joined at their ends to form a rectangular frame. A metal panel 34 is carried by the angle iron frame and

is secured thereto by any convenient means such as bolts 35 (Fig. 5).

Two pairs of lugs 36 are mounted upon the top 6 adjacent the forward end of the machine, one pair of lugs being disposed adjacent each corner of the machine. A lug 37 extends outwardly from one of the angle irons 33 adjacent each corner of the type frame 32 and each lug is adapted to cooperate with the lugs 36 to provide a hinge 38 whereby the frame 32 is swingably mounted upon the top 6 of the machine. Upon the opposite side of the type frame 32, a handle 39 is carried whereby the frame 32 may be conveniently raised or lowered about the hinges 38.

As shown best in Fig. 8, the panel 34 is provided with a plurality of elongated slots 40 which are disposed substantially parallel to each other and are spaced from each other by a plurality of elongated tongues 41. At one end the slots 40 are closed and at the opposite end thereof each of said slots open into a transverse slot 42. As will be hereinafter more fully described, this arrangement permits the convenient mounting and removal of the type bodies employed in conjunction with the present invention.

Each of the slots 40 is adapted to carry a plurality of type bodies 43 (Fig. 15). The type bodies 43 comprise metal members constructed of lead or of the usual type metal, and carry type characters 44 upon one of their faces. The central portion of each of the type bodies 43 is restricted in width as shown best at 45 in Fig. 15, the restricted portion carrying a relatively enlarged head 46 at one end, and a block 47 at the other, the characters 44 being formed upon the outer faces of each of the blocks 47. The construction of the type bodies 43 is such that each of said bodies may be inserted in the slot 42, which is of sufficient width to permit the passage of the head 46 or the block 47 of the type bodies. The bodies are then inserted in the slots 40, the width of the restricted central portions of the bodies being sufficiently small to permit said bodies to be slidably positioned within the slots 40.

It will be noted that the length of the restricted portion 45 relative to the thickness of the panel 34 and hence the thickness of the tongues 41 is such that a degree of movement of the type bodies at right angles to the face of the panel 34 is permitted. For instance, as shown best in Fig. 15, it can readily be seen that the type bodies 43 may move vertically within the slots 40, a distance substantially equal to the thickness of the panel 34. The purpose of this degree of freedom of movement of the type bodies will be hereinafter more fully described.

By reference to Fig. 8, it will be noted that a plurality of the slots 40 are longer than the remaining slots. As shown specifically in this figure of the drawing, the first ten slots 40 comprise relatively long slots whereas the remaining slots are relatively shorter. The arrangement is such that the relatively long slots 40 are each adapted to carry a type body corresponding to each letter of the alphabet, the normal position of the columns of type bodies being adjacent the closed ends of the slots. The shorter slots are adapted to carry type bodies corresponding to numerals from 0 to 9, and the normal position of these type bodies is also adjacent the closed ends of the slots.

Adjacent the side of the type frame 32 opposite to the slotted portion thereof, a plate 48 is mounted by means of bolts 49 or the like, said plate being positioned upon the lower surface of

the type frame 32 as viewed in Fig. 8. The plate 48 is provided with overhanging flanges 49 which function as guides for the slidable reception of a type plate 50.

5 The type plate 50 is of the conventional metallic construction usually employed in "Addressograph" machines, and in itself constitutes no portion of the present invention. The panel 34 adjacent one end of the plate 48 is provided with an aperture 51, whereby the type plate 50 may be slidably positioned upon the plate 48 or removed therefrom from the upper portion of the type frame 32, that is, without inverting said frame.

As will be hereinafter more fully described, predetermined indicia can be printed from the type carried in the slots 40 and the indicia carried upon the type plate 50 by means of the proper manipulation of the letters and numerals comprising the type bodies. It can readily be seen that a predetermined letter or numeral in each slot 40 may be brought to a predetermined aligned position so as to place the characters of these selected type bodies in printing alignment.

The panel 34 on each lateral side of the group of slots 40 is provided with a relatively wide slot 52, and a frame 53 equal in width to substantially the distance between the opposite slots 52 is adapted to be slidably positioned upon the type frame 32. The frame 53 comprises side members 54 which are joined at one end by offset bar 55 (Figs. 8 and 15). At the opposite side of the frame 53, the side members 54 are joined by a flat bar 56. Bolts 57 carried by the frame 53 adjacent each corner thereof extend through the slots 52, said bolts each carrying intermediate its length a rotatable sleeve 58, each having a flange 59 which extends beyond the lateral edges of the slots 52 when said bolts are in operative position. A transversely disposed handle 60 is mounted upon one side of the frame 53 immediately above the cross bar 56.

The arrangement is such that the frame 53, by the proper manipulation of handle 60, may be slidably moved along the length of the slots 52. It will be noted that the flat bar 56 when so moved is in the plane of the heads 46 of the type bodies and, consequently, the edge of said bar is in a position to contact said type bodies to move the same longitudinally within the slots 40. Normally the type bodies are positioned in the slots 40 before the frame 53 is mounted upon the type frame 32 and, consequently, the type bodies in normal position are confined between the closed ends of the slots 40 and an edge of the bar 56.

With specific reference to Fig. 15, it will be noted that when the type bodies 43 are in their lowermost position, the offset bar 55 is disposed in a plane above the heads 46 of the type bodies. The purpose of the bar 55 is, as will be hereinafter more fully described, to move the type bodies to printing position. It can therefore be readily appreciated that the bar 56 is in a position to contact the type bodies at all times, but the bar 55 will only move those type bodies which have been preselected, as will be hereinafter more fully described.

In the operation of the present device, the type bodies 43 are frequently moved along the length of the slots 40. In order to prevent any of the type bodies from being inadvertently moved into the slot 42 when the frame 53 is in its endmost position, the bar 56 is constructed of such width that when bolts 57 contact ends 61 of the slots 52, the inner edge of the bar 56 is spaced from the open ends of the slots 40.

Each pair of lugs 36 upon which the type frame 32 is hingedly mounted carries a pin 62 (Fig. 5), which extends through an aperture 63 provided in the top 6. A coil spring 64 embraces the pin 62 and abuts against the lower surface of the top 6 at one end and at the other end is held in position by washer 65, which in turn is held in position by means of the transverse pin 66 mounted upon the end of the pin 62. It can readily be seen that the construction is such that a degree of resiliency is imparted to the hinged lugs 36 whereby the hinge point may be moved upwardly a predetermined degree against the tension of the springs 64. A pin 67 is mounted upon each lug 37 and serves as a stop when the type frame 32 is in raised position as shown in dotted lines in Fig. 5.

At the opposite side of the type frame 32, an angle piece 68 is mounted adjacent each corner of the type frame. Flange 69 of each angle frame is provided with an aperture in which pin 70 is loosely positioned. Similarly registering apertures are provided in the panel 34 and flange 71 of the angle frame member 33. Each pin 70 is embraced by a coil spring 72 which abuts at one end against the flange 69 and at the opposite end against washer 73 which, in turn, is held in position by pin 74 transversely mounted upon each of the pins 70. The arrangement is such that when the type frame 32 is in lowered position it will initially rest upon the lower ends of the pins 70.

The strength of the springs 72 is such that the normal weight of the type frame will not compress the same and, consequently, the type frame will be disposed in an inclined position as shown best in Fig. 17. A latch 75 pivoted at 76 (Figs. 4 and 6) is disposed adjacent each side of the machine, said latches being positioned operatively with respect to shoulders 77 of the angle frame member 33. As will be hereinafter more fully described, the type frame 32 when in the position shown in Fig. 17 is in a non-printing position. To place the type frame in printing position, the free end of said frame is manually depressed against the compression of springs 72 until latches 75 engage shoulders 77 at which point the type frame 32 is held in the position shown best in Fig. 16.

A plate 78 is positioned beneath panel 34 of the type frame 32 and is carried in spaced relationship with respect to said panel by means of rivets 79 disposed at each corner of the plate 78. The shanks of the rivets 79 extend through apertures provided in the panel 34 and in the plate 78 and each rivet is embraced by a coil spring 80 which abuts at one end against the lower surface of the panel 34 and at the other end against the upper surface of the plate 78.

When the type frame 32 is in the position shown in Fig. 17, the plate 78 is spaced from the panel 34 a maximum distance, said plate being urged away from the panel by means of the coil springs 80. However, when the type frame is depressed to the position shown in Fig. 16, the lower heads of the rivets 79 contact the upper portion of the sheets carried upon the top 6, and coil springs 80 are then compressed to decrease the spacing between the plate 78 and the panel 34.

An elongated slot 81 is provided in the plate 78, the axis thereof extending at right angles to the lengths of the slots 40 which carry the type bodies. As will be hereinafter more fully described, predetermined manipulations of the

type bodies position type bodies carrying desired characters in alignment with the slot 81 and the width of said slot is such that when the type frame is depressed, plate 78 moves upwardly to 5 embrace the aligned type bodies within the slot 81. This alignment of the type bodies constitutes the printing position of said type.

Referring particularly to Figs. 10 and 11, 82 indicates a master or control card which is utilized with the machine comprising the present invention. The card 82 may be of rectangular shape and is preferably constructed of relatively thin metal, stiff cardboard such as resin impregnated cardboard, or of a plastic material. 10 The card 82 is provided with indexing apertures 83 adjacent each corner thereof, and is also provided with opposite notches 84 which are employed in securing the card in proper position upon the machine. If the card 82 is constructed of cardboard or plastic material, relatively thin metal facing members 85 may be positioned adjacent each side of each notch 84 to prevent undue wear of the card at these points incident to mounting the card upon the machine.

The card 82 is provided with a plurality of relatively narrow elongated slots 86 which are disposed parallel to each other. A plurality of slots 86 are longer than the remaining slots, the purpose of which will be hereinafter more fully described. A pin 87 is adapted to be positioned in each of the slots 86, and is slidably movable in said slot. Each pin at one end is tapered 25 concically as shown best at 88 in Fig. 10.

Intermediate the length of each pin, a fixed collar 89 is carried. The opposite end of each pin terminates in a split flange portion 90. In mounting the pins in the slots 86, each pin is inserted into the slot from the rear face of the card and when the collar 89 contacts the card, the split flanges 90 are bent angularly to engage the front face of the card bordering each slot. In this position it can be seen that the flange portions 90 appear upon the front face of the card and the shank of the pin extends rearwardly from the card at right angles thereto.

Adjacent each of the longer slots 86, letters of the alphabet 91 are imprinted in a vertical column. Similarly adjacent each of the shorter slots 86, numerals 92 are imprinted. A flanged strip holder 93 is mounted adjacent the upper edge of the card 82 and is adapted to receive an imprinted strip 94 which may be slidably positioned for convenient removal or insertion in the holder 93. It will be noted that the data imprinted on the strip 94 corresponds to the data printed upon the sheets 18, 19 and 20, that is, the pre-printed data on said sheets which function as column headings for the data which the present machine is adapted to supply.

The card 82 functions as a means for appropriately setting the type carried upon the type frame 32. The specific manner in which the card 82 operates will be hereinafter more fully described. Referring to Fig. 8, it can be seen that the type bodies 43 are all positioned adjacent the closed ends of the slots 40. Each of the type bodies in the relatively long slots 40, correspond to a letter of the alphabet and, consequently, each letter of the alphabet occupies a relatively fixed position with respect to the slot 40. Similarly each type body in each of the shorter slots 40 corresponds to a numeral and that each numeral occupies a fixed position with respect to each short slot 40. The arrangement is such that the printed characters 91 and 92 upon card 82 may

be disposed in coincident relationship with the corresponding characters of the type bodies upon the type frame 32. This relative position on the card of the characters 91 and 92 with respect to the type bodies on the type frame 32 is indexed when the card is employed by engaging indexing pins 95 carried upon panel 34 with the index openings 83.

The card 32 is positioned upon the indexing pins 95 with the pins 87 carried in the slots 85 of the card in downwardly extending position. To fasten the card in this position, a pivotally mounted bolt 96 is positioned adjacent each of the notches 84, said bolts being pivotally secured as at 97 to lugs 98 carried upon panel 34. When the card 32 is placed upon the indexing pins 95, the bolts 96 are swung inwardly into notches 84, and knurled nuts 99 threadedly mounted upon the bolts 96 are rotated to securely engage the card 32 in position.

The indexing pins 95 are enlarged in diameter at their lower portions as shown best at 100 in Fig. 16 whereby card 32 may be positioned in predetermined spaced relationship with respect to the upper surface of the panel 34. The heads 46 of each of the type bodies 43 are provided with conical apertures 101, with which the conical points 83 of pins 87 register when the card 32 is positioned properly upon index pins 95.

To set the type bodies in proper printing position to print predetermined data upon record sheets such as the sheets 18, 19 and 20, the type frame 32 is swung about its hinged mount to the position shown in Fig. 17. The frame 54 which is slidably positioned upon the type frame is then moved to position shown in Fig. 8, thus confining all of the type bodies in columns, resting upon the ends of the slots 40. As has been hereinbefore described, when the type bodies are in this position, they correspond in relationship and position with the printed indicia 91 and 92 upon card 32. With the type frame 32 and the frame 54 in the above described position, the machine is then adapted for the reception of the card 32.

In preparing the card 32 for mounting upon the machine, the pins 87 are moved to appropriate positions along slots 85 as indicated by the letters 91 or numerals 92 in order to arrange, upon reading from left to right, the data which is to be printed upon the sheets 18, 19 and 20. For example, the first numeral comprises the "Check No." which has been arbitrarily selected as "3132". Under the proper heading as indicated by the strip 94, the pin 87 in the first numeral column is moved to the "3" position; in the next column the pin is moved to the "1" position; in the next column the pin is moved to the "3" position, and in the last column the pin is moved to the "2" position. In similar fashion the pins in the slots 86 under the appropriate columns are moved to indicate the desired numerals.

In the event that some other information with regard to the transaction involved is to be imprinted upon the record sheets, the pins in the columns "Misc. Information" heading would be moved to appropriate positions. Where these latter columns are employed, only one line of printing is contemplated.

With the pins upon the card 32 appropriately set as hereinbefore described, the card 32 is positioned upon the indexing pins 95 and the bolts 96 are swung to locking position and the nuts 99 are appropriately manipulated to lock the card 32 in such position.

In view of the fact that the letters 91 and

numerals 92 upon the card 32 correspond in alignment with appropriate type bodies 43 upon the type frame, the conical points 83 of the pre-set pins 87 will register with the conical openings 101 of those type bodies having characters 44 corresponding to the position of the pins on the card as indicated by the numerals and letters.

With all of the elements in the pre-set position described hereinbefore, the frame 54 is moved along slots 52 and as said frame moves, the offset bar 55 contacts the shanks of the pins 87, thereby moving said pins within the slots 86. The frame 54 continues its movement until it reaches the endmost position, as shown best in Fig. 1. At this time the offset bar 55 will have moved to a position wherein all of the pins are in substantial alignment with the slot 81 in the plate 78. In other words, all of those type bodies which had previously been selected by the proper setting of the pins 87 on the card 32, have now been moved to printing position. In this position it will be noted that a number of the type bodies have been moved into the upper portions of the slots 40 of the type frame, and the remaining type bodies remain undisturbed within slots 40 adjacent the closed ends thereof.

If it is desired to qualify the data to be printed upon the record sheets 18, 19 and 20 by employing a multi-line designation such as indicated by the name and number "John Doe 123-000-45," an appropriately off-set plate 59 may be positioned in the holder 48. It will be noted that the off-set type of the plate 59 will be in substantial alignment with the line of type bodies in the printing position.

With the type bodies and plate 59 thus set, the free end of the type frame is depressed thereby compressing coil springs 72 and engaging the shoulder 32 with the latches 75. By depressing the type frame those type bodies which are in alignment with the slot 81, have their faces protruding through the slot 81 as shown best in Figs. 15 and 16, by virtue of the fact that the plate 78 is moved upwardly against the compressive force of the springs 80.

A shaft 102 is journaled in each of its ends in bearings 103 positioned in bosses 104, formed upon the side frame members 2 and 3. A collar 105 is secured to an end of shaft 102 by means of set screw 106, said collar carrying a crank arm 107 upon which is mounted a handle or knob 108 whereby said arm may be conveniently manipulated to rotate shaft 102. A pair of links 109 and 110 are mounted upon shaft 102 adjacent opposite sides of the machine, said links being secured to the shaft 102 by means of set screws 111.

The upper portion of each of the links 109 and 110 is provided with a slot 112 in which a shaft 113 is carried. The shaft 113 in turn carries a pressure roller 114 which is preferably of metallic surface construction. A channel iron 115 is secured to the bottom 6 and the side frame 2, and a similar channel iron 116 is secured to the lower face of the top 6. Both of the channels 115 and 116 open toward each other and are adapted to carry ball bearing assemblies 117 mounted upon the opposite ends of shaft 113.

By swinging the crank arm 107, shaft 102 is rotated which in turn swings arms 109 and 110. A force is thus exerted upon shaft 113 to move said shaft and by virtue of the slots 112 and the fact that the ball bearing assemblies 117 rest upon the lower flange of the channels 116,

11

the movement of the roller 114 takes place in a substantially horizontal plane. Immediately above roller 114 the top 6 is provided with an aperture 118, said aperture being positioned immediately below the slot 81 in plate 78. It can readily be seen that when the roller 114 is moved and the type frame 32 is in printing position, the roll presses the various webs disposed upon the top 6 into contact with those faces of the type bodies 43 which are positioned in the slot 81. In this manner a printing impression is made upon the various record sheets which may be interposed between the type bodies in the slot 81 and the roll 114.

In a similar manner the roll 114 exerts pressure upon the offset characters formed in the plate 50 and, consequently, the indicia carried by said plate is also imprinted upon the record sheets.

A ratchet 119 is rotatably but non-slidably mounted upon shaft 102 adjacent link 110. A spring pressed detent 120 is mounted by means of bolt 121 upon an intermediate portion of arm 110, the arrangement being such that rotary motion of shaft 102 in one direction merely causes the detent to slide over the teeth of the ratchet 119, whereas rotary motion of said shaft in an opposite angular direction causes the ratchet to move in step with the shaft.

In other words, when the crank arm 107 is moved in the direction indicated by the arrow in Fig. 6, the detent 120 operates over the ratchet teeth whereas movement of the crank arm in the opposite direction causes the detent to engage the ratchet teeth and, hence, rotate the ratchet in step with the shaft 102.

Formed integrally with the ratchet 119 is a pinion 121 which engages with gear 122, as shown best in Fig. 12. Gear 122 is loosely mounted upon shaft 123 which is secured to the side frame 3. A wheel 124 is rigidly mounted with respect to the gear 122 and is adapted to move in unison therewith. The periphery of wheel 124 carries a plurality of radially projecting circumferentially spaced pins 125, and the upper periphery thereof extends through slot 126 provided in the top 6.

Referring particularly to Fig. 18, it will be noted that the pay roll journal 18 is provided with a plurality of aligned apertures 127, which, when the web comprising the pay roll journal is positioned upon the top 6, engage with the pins 125. In this manner the pay roll journal 18 is moved stepwise with movement of the arm 107 in one direction.

In order to prevent movement of the ratchet 119, gear 121, gear 122 and wheel 124 with movement of the shaft 102 in the direction indicated by the arrow in Fig. 6, a ratchet wheel 128 is mounted upon shaft 123 as an integral portion of the gear 122—wheel 124 assembly. A detent 129 is mounted upon the side frame 3 and is pressed by spring 130 into contact with the ratchet teeth of the wheel 128. Hence, when the arm 107 is moved in the direction of the arrow as indicated in Fig. 6, the detent 129 engages the ratchet teeth of the wheel 128 and prevents movement of the gear assembly above described. When the detent 120 engages the ratchet 119 on the reverse movement of the shaft 102, the detent 130 slides over the ratchet 128.

A coil spring 131 is secured to each of the links 109 and is anchored at its opposite end upon a rod 132 which is carried by each of the side frames 2 and 3. The function of the springs

12

131 is to cause links 109 and 110 to be swung in a direction opposite to the arrow, as indicated in Fig. 6, when the crank arm 107 has been moved to the position shown in dotted lines in said figure. Hence, it can be seen that the arm 107 is moved manually in one direction to move roll 114 horizontally, and is moved in the opposite direction under the tension of springs 131.

A bar 133 is pivotally secured at one of its ends to the link 110 and a similar rod is similarly carried by the link 109. The opposite end of each of said rods is provided with a slot 134 in which a transverse rod 135 is positioned. The rod 135 is carried at the lower ends 136 of the latches 75. A coil spring 137 is secured to the end of each of the bars 133 and at the opposite ends of said springs they are anchored to pins 138 carried on the side frames 2 and 3.

The arrangement is such that when the type frame 132 has been depressed to permit engagement of the latches 75 with the shoulders 77, thereby holding the type frame in printing position, movement of the arm 107 in the direction of the arrow, as indicated in Fig. 6, causes links 133 to move freely with respect to the rod 135. However, when the arm 107 approaches closely the position shown in dotted lines in Fig. 6, the ends of the bars 133 contact the rod 135 and rock the latches about their pivot points 76, thus disengaging the latches 75 from the shoulders 77 and permitting the type frame 32 to move upwardly to the position shown in Fig. 17. In this position the faces of the type bodies in the slot 81 are moved upwardly out of the printing position. Hence, when springs 131 returned the arms 109 and 110 to normal position, the roll 114 will not function to cause a second impression to be made upon the record sheets since the faces of the type bodies, at this time, are spaced from the upper surface of the webs upon the top 6. In addition, by virtue of the fact that the type frame has been raised, reverse movement of the arm 107 and hence of the roller 114, permits the pay roll journal web 18 to be moved stepwise by the wheel 124.

As has been hereinbefore described, the pay-roll journal 18, shown in the form of web 25 is threaded from roll 24 over the top 6 of the machine and wound upon take-up roll 28, which, if desired, may be a spring actuated roll which will automatically wind up the web as slack becomes available. A carbon paper web 12 is positioned over the web 25 and the earnings record sheet 19 is positioned on top of the web 12. To locate properly the sheet 19, a clip 139 is slidably positioned upon elongated, upraised strip 140 which, in turn, is carried upon the top 6. The clip 139 is provided with a folded tab, as shown best at 141 in Fig. 1, which is adapted to embrace the lower corner of the sheet 19 to orient the sheet properly with respect to the type bodies in the slot 81. The face of the strip 140 is provided with calibrated indicia 142 whereby the clip 139 may be positioned in a predetermined manner to expose a predetermined line upon the sheet to the printing operation. The carbon web 11 is positioned over the sheet 19 to serve as a pigmenting medium for said sheet. Check 20 is then disposed over the web 11 in appropriate position with respect to the active line of type bodies.

It is desirable to have the upper record sheet, whatever record sheet it may be, that is, the check 20 in the present illustration, exposed so that, after the printing operation is performed, the

type frame can be raised and the line of printing upon the check conveniently verified without the necessity of removing a fixedly positioned carbon paper web, such as webs 11 or 12. To accomplish this purpose a pair of lugs 143 are mounted upon each angle member 33 on opposite sides of the type frame 32. Each pair of lugs 143 carries a spindle 144 upon which a web of carbon paper 145 may be wound in the form of a roll 146. The axis of the web 145 is disposed substantially beneath the slot 81 when the type frame 32 is in printing position whereby pressure by roll 144 causes a printing impression to be formed upon check 20. To move conveniently the web 145, knurled knobs 147 are mounted upon the spindles 144.

For purposes of illustration, a complete cycle of operation of the machine hereinbefore described is set forth as follows:

With the type frame 32 in raised position as shown in dotted lines in Fig. 6, and with the pay roll journal sheet, shown as the web 25, threaded upon the take-up roll 29, the earnings record sheet 19 may be positioned between carbon paper webs 11 and 12, and may be properly oriented by means of the clip 139. A check 20 may then be positioned over the carbon paper web 11.

The type frame 32 may then be swung downwardly to the position shown in Fig. 17, and the frame 53 may be moved to the position shown in Fig. 8, wherein all of the type bodies 43 in the slots 40 are moved to the closed ends of said slots.

A master or control card 82 may then have its pins 87 appropriately positioned in the slots 86 to designate predetermined data which is to be entered upon the record sheets. The master card with the pins so set may then be positioned over the type frame 32 by disposing said card over the indexing pins 95 and fastening the card in position by means of the nuts 99. In so positioning the card over the type frame the conical points of the appropriately set pins 87 will register with the conical openings in the heads of corresponding type bodies 43. The slideable frame 53 is then moved in the slots 52 and the offset bar 55 engages the pins which project from the master card 82, moving the respective type bodies with which said pins are engaged, and hence, moving all of the type bodies to positions in the respective slots above the engaged type bodies. In this manner all of the engaged or pre-selected type bodies are moved to a printing position, that is, they are moved in alignment with slot 81 in plate 78.

The type frame 32 is then depressed to cause the latch 75 to engage the shoulder 77. The depression of the type frame comprises spring 72 and springs 80 whereby the pre-selected type bodies protrude through the slot 81 and the faces thereof are in substantial contact with the uppermost carbon web, that is, the web 145, which is disposed transversely across the machine. The arm 107 is then moved in a counterclockwise direction, as viewed in Fig. 6, thereby moving the roll 114 into pressure contact with the web assembly confined beneath the faces of the pre-selected type bodies. An impression is thereby produced upon the record sheet hereinbefore described. Simultaneously, a record is also made by the embossed face of the plate 50.

When the arm 107 has been moved to the position shown in dotted lines in Fig. 6, the latches 75 are disengaged from the shoulders 77 by means

of the bars 133. This action permits the type frame to move upwardly under the influence of springs 72 to the position shown in Fig. 17. During the period that the arm 107 moves in a counterclockwise direction, as viewed in Fig. 6, the detent 120 slides freely over the ratchet teeth 119. The assembly of gears associated with the ratchet teeth, namely, gears 121 and 122, are held in fixed position by means of the detent 129, which engages the teeth of ratchet wheel 128 and holds said assembly in fixed position during counterclockwise movement of arm 107.

However, after the arm 107 has been moved to the position in dotted lines in Fig. 6, the operator releases said arm and under the influence of springs 131, said arm moves in a clockwise direction. In view of the fact that the type frame 32 at this period is in upraised position, the movement of the roll 114 will not cause an impression to be made upon the various record sheets. When, however, the arm 107 moves in clockwise direction, detent 120 engages the ratchet wheel 119 causing gears 121 and 122 to move. This movement, in turn, imparts movement to the wheel 124, and the pins 125 carried upon said wheel and engageable with apertures 127 in the pay roll journal web, moves said web a predetermined degree so that said web is in position to receive the next line of printing. During this latter movement the detent 129 slides freely over the teeth of the ratchet wheel 128.

The frame 53 is then slidably moved to its original position as shown best in Fig. 8. This movement of the frame causes bar 55 to contact the endmost type bodies carried in the slots 40, that is, those type bodies in the respective slots which are closest to the slot 42. Continued movement of the frame 53 slides each column of type bodies within the respective slots 40 until the frame 53 reaches its lowermost position as shown in Fig. 8.

Movement of the column of type bodies by the reverse movement of the frame 53 as hereinbefore described, also moves pins 87 which are carried upon the master card 82. Said pins are then moved from the printing position, shown best in Fig. 1, to the position that they had previously occupied as when originally set. The card 82 may then be removed from its operative position upon the machine and another pre-set card may be substituted therefor after, however, a new check 20 has been inserted in the machine and after the clip 139 has been moved upwardly along the card member 140 and a new earnings record sheet has been inserted. The printing operation hereinbefore described, can then be repeated.

It will be noted that the card 82, in addition to functioning as a master or control card in connection with the proper positioning of the type bodies, also constitutes a record in itself. As has been hereinbefore described, the pins 87 upon said card are initially moved to appropriate positions within the slots 86 to designate upon the indicia 91 and 92, appropriate data. The card then functions as an instrumentality for controlling the positioning of appropriate type bodies to reproduce said data upon the record sheets. Subsequently, when the frame 55 has been returned to its normal position, the pins 87 are returned to their pre-set position and, hence, the card 82 also constitutes a record upon which the appropriate data appears. This card may then be filed as a master record of the transaction which has been recorded upon the hereinbefore described record sheets. If desired, the pins 87,

15

after the card 82 has functioned in its control capacity, may be returned to their uppermost positions within the slots 86.

Although the present invention has been described in conjunction with the preparation of the maintenance of pay roll records, many other uses for the invention suggest themselves to any one skilled in the art. For example, the card 82 may be used as an instrumentality in the maintenance of a physical inventory record system. The card 82, with approximate headings inserted on the strip 94 may be positioned for instance, adjacent a bin, shelves, or other container in which a predetermined item of stock may be stored. When a quantity of such stock has been removed from the stock container or a quantity thereof has been supplied thereto, the operator may manipulate pins 87 upon said card to indicate the nature of the operation, that is, the pins may indicate, for instance, that a certain number of items have been extracted; it may also indicate the cost of said items, etc.

By appropriately adjusting the position of the pins 87 upon the card over a period of time, a running record may be maintained of the amount of goods deposited or removed from a predetermined container. When stock records are to be adjusted, it is merely necessary to remove said card and insert the same in a machine such as hereinbefore described, and the data, which may be the result of transactions which were carried on over a long period of time, may then be reduced to printed form on any desired number of printed records.

In order that the pins 87 may be placed to an inoperative position upon the card 82, an upper row 148 of positions is provided. When the pins 87 are in this upper row, they will not function to engage any of the type bodies inasmuch as there is no horizontal row of type bodies with which the row 148 registers. In those columns devoted to the alphabet, a row 149 of dashes is indicated. In the same horizontal position with said row, but in the columns devoted to the numerals, a row of decimal points is provided. In the numeral column a row of dashes 150 is positioned immediately beneath the row of decimal points.

Referring particularly to Figs. 30, 31 and 32, a modification of the master or control card is illustrated. The card 151 is constructed similar to the card 82 in that it is provided with index openings 152 and slots 153 whereby the same may be mounted upon the machine hereinbefore described. The body of the card also carries slots similar to the slots 86 which are designated by indicia similar to the indicia 91 and 92. The area indicated by the reference numeral 154 is intended to illustrate the position occupied by the rows of slots similar to slots 86.

As a feature of the card 151, a pair of extensions 155 and 156 project laterally from the card, said extensions being adapted to function as holders for an impression plate 157. The extension 155 is provided with a portion 158 which is folded in a U-shape and similarly the extension 156 is provided with a folded portion 159 whereby opposite slots are provided for the reception of flanges 160 formed upon the cup-shaped plate 157. The bottom portion of the plate 157 is embossed as indicated at 161 in Fig. 31 so as to outline desired data which is subsequently used for impression purposes.

Referring particularly to Fig. 32, it will be noted that the impression surface 161, by virtue of the cup-shape of the member 157, is disposed

16

in a plane substantially coincident with the plane of the faces 44 of the type bodies 43. By occupying this position, movement of the pressure roller 114 beneath the record sheet-carbon paper assembly functions to press said assembly into printing contact with the impression surface 161 simultaneously with the pressing of the assembly into contact with the faces 44 of the type bodies.

The advantage of the master or control card 151 is that the plate 157 is carried thereon as a unitary portion of the card, the plate 157 being positioned on the machine at the same time that the card is positioned thereon. Likewise, in view of the fact that the card in some instances constitutes a record in itself, the plate 157 being mounted on said card, functions to identify said plate at all times.

Referring particularly to Figs. 21, 22, 23 and 24, a modification of the present invention is illustrated. In this form of the invention a master or control card is not employed in positioning the type in printing position. For purposes of clarity of description the identical parts of the machine, as hereinbefore described will be referred to by the same reference numerals hereinbefore used and those portions only which differ in physical form or function will be described, it being understood that the remaining portion of the machine will function in a manner as hereinbefore described.

In this form of the invention type frame 32 is hingedly mounted upon the machine, as hereinbefore described and panel 34 is provided with a plurality of slots 40 for the reception of the type bodies 149. The type bodies 149 employed are similar to type bodies 43 except that instead of conical indentations in the heads thereof type bodies 149 have indicia inscribed upon the upper faces of the heads, such as, letters of the alphabet 150 or numerals 151 which correspond with the printing faces 44 of the respective bodies. The same number of type bodies in each slot 40 are contemplated.

An offset bar 152 is mounted upon panel 34 by means of bolts or the like 153, said bar being positioned immediately above the slot 81 in plate 78, that is, in alignment with the printing position of the type bodies. Bar 152 is provided with an elongated aperture 154 whereby the indicia 150 and 151 of the type bodies in printing position may be observed by the operator thus permitting verification of the setting before completing the printing operation.

A plate 155, having an inwardly turned flanged edge 165 is mounted upon bar 152 and secured thereto by means of machine screws or the like 156. The plate 155 is adapted to carry a guide strip 157 which is provided with data 158 indicative of the matter to be typed, said data being the same as may appear upon the record sheets. In this manner the operator is provided with a guide in the setting of the type bodies in proper columnar position.

In the operation of this modified form of the invention, the record sheets and carbon webs are disposed in the same manner as has been hereinbefore described. The type frame 32 is then disposed in its semi-closed position similar to the position illustrated in Fig. 17. The type bodies 149 may then be moved manually within the slots 40 to bring the desired type bodies into a position wherein they are visible through the slot 154. In this position the selected type bodies are disposed immediately above the slot 81 in the plate 78. The type frame 32 is then swung

downwardly to its operative printing position, wherein the latches 75 engage the shoulders 77.

The plate 78 thus moves upwardly against the compression of springs 80 and the faces of the selected type bodies protrude through the slot 81. The arm 107 is then swung in a counter-clockwise direction, similar to the motion indicated in Fig. 6 whereby the roll 114 establishes pressure upon the record sheet-carbon web assembly, and the faces of the selected type impress upon the record sheets the data resulting from the selection of the appropriate type bodies.

When the arm 107 reaches its endmost position, the latches 75 release the type frame and upon release of the arm 107 the roll 114 returns to its normal position, the action of said arm 107 in returning to its normal position causing movement of the wheel 124, which in turn moves the web 25 in stepwise fashion.

Referring particularly to Figs. 25, 26, 27, 28, 29, another modification of the invention is shown. In the form of the invention, loose, individual type bodies are not employed, the printing being accomplished by rotary type discs. The remaining portion of the machine is similar to that hereinbefore described and such similar parts will be referred to by the reference numerals hereinbefore employed.

In this form of the present invention, a type frame 159 is employed, said frame having ends 160 and 161, and sides 162 and 163. The side 163 carries projecting lugs 164 which are hingedly secured by means of bolts 165 to lugs 36 carried upon the top 6 whereby the frame 159 may be swung about said hinges.

The type frame 159 carries a panel 166 at its top, which is supported by the ends 160 and 161 and sides 162 and 163. A pair of angle irons 167 are mounted upon side 163 beneath top 166 and adjacent each corner of the type frame. One flange 168 of each angle iron is provided with an aperture for the reception of a pin 169. The side 163, at its bottom, has a pair of turned flanges 170, which are also provided with apertures registering with the apertures in the flanges 168 in which pin 169 is positioned.

A coil spring 171 embraces each pin 169 and its abutments, at one end, against each flange 168, the opposite end of said coil springs abutting washers 172, which embrace pins 169, said washers being supported by transversely extending pins 173 mounted upon the pins 169. The side 163 is also provided with a pair of recesses 174 with which the latches 75 are engageable when the type frame 159 has been moved to its lowermost position.

When the type frame 159 is in the position shown in Fig. 25, that is, when latch 75 is engaged in apertures 174, springs 171 are compressed. When latch 75 is released, as hereinbefore described by the operation of the arm 107, the end 163 of the type frame springs upwardly under the influence of springs 171, thereby removing the type from operative printing position, as will be hereinafter more fully described.

A web 175 having flanges 176 and 177 is mounted upon the lower face of panel 166 at an intermediate portion thereof, the flange 177 is mounted upon a supporting bar 178, the opposite end of which is mounted upon flange 170. A second web 179 is mounted upon the lower face 70 of panel 166 and is spaced from the web 175.

A shaft 180 is carried by webs 175 and 179, the being rigidly secured to said webs by cap screws 181. A plurality of disks 182 are rotatably mounted upon shaft 180, the periphery of said

disks carrying type faces 183 which may comprise letters of the alphabet, numerals or the like, said type faces being circumferentially spaced from each other. Adjacent each disk 182 is a gear wheel 184 which is secured to one of the disks 182, that is, one gear wheel 184 is secured to each disk 182, said gear wheels being alternately spaced with respect to the disks. The arrangement is such that rotation of one of the gear wheels 184 imparts rotation to its companion disk 183, all of the sets of gear wheels and disks being movable independently of each other.

The upper panel 166 is provided with a plurality of elongated parallel disposed slots 185, each of said slots being in vertical alignment with each gear wheel 184. A rack 186 is positioned in each slot 185, said rack having gear teeth 187 which are adapted to mesh with the gear teeth of each wheel 184. A handle 188 is carried at the end of each rack 186 whereby said rack may be moved longitudinally within its confining slot 185 in order to rotate the respective gear wheel 184 with which the rack is engaged.

The portion of the panel 166 interposed between each pair of racks, as shown best at 189 in Fig. 29, is provided with indicia 190. A projecting pointer 191 is carried upon the side of each rack 186, said pointer being adapted to ride over the indicia 190 when the rack is longitudinally moved within its slot 185. The arrangement is such that registration of the pointer 191 with a predetermined numeral or letter of the alphabet 190, will indicate that the corresponding numeral or letter of the alphabet carried upon the type faces 183, is positioned at the lowermost position upon the disk 182 as indicated at 192 in Fig. 25.

In other words, the pointer 191 indicating a predetermined numeral or letter of the alphabet or the like, 190, informs the operator that the corresponding type face 183 is disposed in printing position.

An offset bar 193 is positioned upon the upper portion of panel 166, said bar being adapted to bridge the parallel racks 186. The bar 193 carries flanges 194 along opposite edges thereof whereby a removable data strip 195 may be positioned upon said bar. The data strip 195 carries various items of data corresponding to the headings upon the record sheets which are to be printed and said data strip being positioned as hereinbefore described serves as a guide to the operator in the proper manipulation of the racks 186 in order to bring appropriate type faces to the printing position in alignment with the appropriate columns upon the record sheet.

In operation the type frame 159 is moved to its pre-printing position, that is, to a position corresponding to the position illustrated in Fig. 17. The various racks 186 are then manipulated to bring the desired type faces upon the disks 182 into the printing position as indicated in 192 in Fig. 25. The record sheets and carbon paper webs having already been disposed upon the top 6 of the machine, are ready to receive the printed data. The type frame 159 is then moved to its printing position, that is, the position illustrated in Fig. 25 wherein the latches 75 engage in the notches 174.

The handle 107 is then moved, as hereinbefore described, to cause roll 114 to establish pressure upon the record sheet-carbon paper web assembly, thus forcing said assembly into contact with the type faces which have previously been disposed in the printing position 192. In this man-

ner the appropriate data is printed upon the record sheets.

When the arm 107 moves through its endmost position, the latches 75 are released from the notches 174, and the free end of the type frame 159 moves upwardly under the influence of springs 171, thereby moving the type faces 103 out of contact with the record sheet-carbon paper web assembly. Hence, when the arm 107 moves to its reverse position under the influence of springs 131, no printing or smudging of the record sheets takes place. Simultaneously, with the reverse movement of the arm 107, the web 25 is moved by wheel 124, as has been hereinbefore described.

I claim as my invention:

1. A printing machine comprising in combination, a frame, means for carrying record sheets interleaved with duplicating material upon said frame, a type frame swingably mounted at an end of said frame and above said record sheets, movable type characters carried upon said type frame, means for selecting and disposing predetermined type characters in printing position upon said type frame, means for locking said type frame in operative position above said record sheets with the type faces extending downwardly and in proximity to and in confronting relationship with said record sheets, means for reciprocally pressing said record sheets and interleaved duplicating material against said predetermined type characters carried in said printing position to imprint said record sheets with duplicate data, means connecting said locking means and pressing means for unlocking said type frame at the end of the pressing operation, and resilient means for moving said type frame upwardly to inoperative position with the type faces spaced a predetermined distance above the record sheets after the printing of said duplicate data.

2. A printing machine comprising in combination, a frame, means for carrying record sheets interleaved with duplicating material upon said frame, a type frame mounted upon said frame, movable type characters carried upon said type frame, means for selecting and disposing predetermined type characters in printing position upon said type frame for each printing operation, the type faces of said selected type characters being disposed in proximity to and in confronting relationship with said record sheets, means for locking said type frame in operative printing position above said record sheets, and a pressure roll mounted upon said frame and movable a limited distance over and beyond said printing position for pressing said record sheets and duplicating material into printing contact with said predetermined type characters carried in said printing position to imprint duplicate data upon said record sheets, and means for unlocking the type frame when the pressure roll has moved a predetermined distance beyond the printing position.

3. A printing machine comprising in combination, a frame, means for carrying record sheets interleaved with duplicating material upon said frame, a type frame mounted upon said frame, type characters movably carried upon said type frame, means for disposing predetermined of said type characters in printing position upon said type frame, means for locking said type frame in operative position above said record sheets, a pressure roll mounted upon said frame and transaxially movable a limited distance for pressing said record sheets and duplicating material

into printing contact with said predetermined type characters carried in said printing position to imprint duplicate data upon said record sheets, means mounted upon said frame for unlocking said type frame when said roll has reached its limited movement, and resilient means carried by said type frame for moving said frame to inoperative position when said frame is unlocked.

4. A printing machine comprising in combination, a frame, means for carrying record sheets and interleaved duplicating material upon said frame, a type frame movably carried upon said frame, type bodies carrying type characters slidably positioned in parallel slots provided in said type frame whereby predetermined type bodies may be selectively moved to a predetermined printing position upon said type frame, a plate mounted upon said type frame beneath said type frame, said mounting comprising resilient means whereby said plate is resiliently movable with respect to the bottom of said type frame, said plate being provided with an elongated slot defining the printing position for the selected type bodies, means for locking said type frame in operative position above said record sheets, said selected type bodies being confined in the slot in said plate when the type frame is moved to locked position, and means for pressing said record sheets and duplicating material against said type characters of the type bodies carried in said printing position to imprint duplicate data upon said record sheets.

5. A printing machine comprising in combination, a frame, means for carrying record sheets and interleaved duplicating material upon said frame, a type frame movably carried upon said frame, type bodies carrying type characters slidably positioned in parallel slots provided in said type frame whereby predetermined type bodies may be selectively moved to a predetermined printing position upon said type frame, a plate mounted upon said type frame beneath said type frame, said mounting comprising resilient means whereby said plate is resiliently movable with respect to the bottom of said type frame, said plate being provided with an elongated slot defining the printing position for the selected type bodies to expose only the type characters of said selected type bodies, means for locking said type frame in operative position above said record sheets, said selected type bodies being confined in the slot in said plate when the type frame is moved to locked position, and means for pressing said record sheets and duplicating material against said type characters of the type bodies carried in said printing position to imprint duplicate data upon said record sheets.

6. A printing machine comprising in combination, a frame, means for carrying record sheets and interleaved, duplicating material upon said frame, a type frame swingably mounted upon said frame, resilient means for holding said type frame in a predetermined position above said frame, type bodies slidably carried in parallel slots provided in said type frame, a plate resiliently positioned upon said type frame and carried beneath said frame, said plate being movable toward and away from the type frame, an elongated slot provided in said plate, means for moving predetermined selected type bodies in said slots to a printing position above the slot in said plate, said type frame being movable from said predetermined position to a printing position, means for locking said type frame in said

latter position, movement of said type frame toward said means comprising a control card, pins moving printing position moving said plate toward said card, whereby said control card whereby said type frame, to dispose portions of the type bodies and pins are adapted to be disposed in predetermined positions in the slot in said plate, and means for pressing said positions upon said card, said pins projecting from said record sheets and duplicating material into said slot from the card, whereby the ends thereof engage printing contact with the type bodies in printed word with predetermined type bodies, means for moving positions to imprint duplicate data upon the record sheets upon said pins upon the card, to move said predetermined type bodies to printing position upon said record sheets.

7. A printing machine comprising in combination, a frame, means for carrying record sheets, record sheets and duplicating material against and interleaved duplicating material upon said frame, type frame movably carried upon said frame, type bodies carrying type characters slidably positioned in parallel slots provided in said frame, type frame movably carried upon said frame, type frame movably carried upon said frame, type bodies being provided with recesses, means carried upon said type frame for moving predetermined type bodies in said frame, type bodies carrying type characters to a predetermined printing position, said means slidably positioned in parallel slots provided in said frame, comprising a control card, pins movably carried upon said type frame, means carried upon said type frame for moving predetermined type bodies in said frame, having their ends projecting therefrom into engagement with recesses in said slots, to a predetermined printing position, in predetermined type bodies, means for moving said pins, said means comprising a control card, pins moving said pins to move said predetermined type bodies movably carried upon said control card, whereby said pins to printing position, and means for pressing said pins are adapted to be disposed in predetermined record sheets and duplicating material against positions upon said card, said pins projecting from the type bodies in printing position to imprint data from the card, whereby the ends thereof engage with predetermined type bodies, means for moving duplicate data upon said record sheets.

8. A printing machine comprising in combination, said pins upon the card to move said predetermined type bodies to printing position upon said frame, record sheets and duplicating material against frame, type frame movably carried upon said frame, type bodies carrying type characters slidably positioned in parallel slots provided in said frame, type frame movably carried upon said frame, type bodies being provided for moving said pins and said predetermined type frame provided with a recess, means carried upon said type frame for moving said pins to their original positions upon said card frame, for moving predetermined type bodies in said frame, respectively, after the printing operation has been completed, said means comprising a control card, pins moving predetermined type bodies to printing position, and means for carrying record sheets and interleaved duplicating material upon said frame, a type frame movably carried upon said frame, type bodies carrying type characters slidably positioned in parallel slots provided in said type frame, means carried upon said type frame for moving predetermined type bodies to printing position, and means for pressing said record sheets and duplicating material against the type bodies in printing position to imprint duplicate data upon said record sheets.

9. A printing machine comprising in combination, a frame, means for carrying record sheets, record sheets and interleaved duplicating material upon said frame, type frame movably carried upon said frame, type bodies carrying type characters slidably positioned in parallel slots provided in said frame, type frame movably carried upon said frame, type bodies carrying type characters slidably positioned in said slots where by said pins are adapted to be disposed in predetermined positions upon said card, said pins projecting from the card, whereby the ends thereof engage with predetermined type bodies, means for moving said pins in the slots in said card, to move predetermined type bodies to printing position, and means for pressing said record sheets and duplicating material against the type bodies in printing position to imprint duplicate data upon the record sheets.

10. A printing machine comprising in combination, a frame, means for carrying record sheets and interleaved duplicating material upon said frame, type frame movably carried upon said frame, type bodies carrying type characters slidably positioned in parallel slots provided in said frame, means carried upon said type frame for moving predetermined type bodies in said slots to a predetermined printing position, and means for pressing said record sheets and duplicating material against the type bodies in printing position to imprint duplicate data upon the record sheets.

13. A control card for printing machines of the type comprising a type frame carrying movable type bodies disposed in predetermined relationship upon said type frame and means for pressing sheets to be printed into printing contact with preselected type bodies, comprising a relatively rigid sheet, indicia upon said sheet corresponding to the positional relationship of the type bodies on the type frame, and movable means carried upon said sheet indexed by said indicia and adapted to engage predetermined type bodies upon said type frame and move said predetermined type bodies preselected by the position of said movable means upon said sheet.

14. A control card for printing machines of the type comprising a type frame carrying mov-

able type bodies disposed in predetermined relationship upon said type frame and means for pressing sheets to be printed into printing contact with preselected type bodies, comprising a relatively rigid sheet, indicia upon said sheet corresponding to the positional relationship of the type bodies on the type frame, and movable pins carried upon said sheet indexed by said indicia and adapted to engage predetermined type bodies upon said type frame and move said predetermined type bodies preselected by the position of said movable means upon said sheet.

15. A control card for printing machines of the type comprising a type frame carrying type bodies movable in predetermined rows to a printing position and means for pressing sheets to be printed into printing contact with preselected type bodies, comprising a relatively rigid sheet having a plurality of slots corresponding to the rows of type bodies upon the type frame, indicia carried by said sheet adjacent said slots corresponding with the type bodies in said rows, and means movably positioned in said slots adapted to engage predetermined type bodies as determined by said indicia upon said type frame and moving the same to printing position.

16. A control card for printing machines of the type comprising a type frame carrying type bodies movable in predetermined parallel rows to a printing position and means for pressing sheets to be printed into printing contact with preselected type bodies, comprising a relatively rigid sheet having a plurality of parallel slots corresponding to the rows of type bodies upon the type frame, indicia carried by said sheet adjacent said slots corresponding with the type bodies in said rows, and means movably positioned in said slots adapted to engage predetermined type bodies as determined by said indicia upon said type frame and move the same to printing position.

17. A printing machine comprising in combination, a frame, means for carrying record sheets interleaved with duplicating material upon said frame, a type frame swingably mounted at an end of said frame above said record sheets, movable individual type characters carried upon said type frame, means for selecting predetermined individual type characters for each printing operation, means for disposing said selected type characters in printing position upon said type frame with the type faces of said selected type characters disposed in proximity to and in confronting relationship with said record sheets, means for locking said type frame in operative position above said record sheets to dispose said selected type characters in printing position, and means for reciprocating said record sheets and interleaved duplicating material upwardly into printing contact with said selected type characters carried in the printing position to imprint said record sheets with duplicate data, and means for unlocking said type frame after said record sheets have been imprinted with said duplicate data.

18. A printing machine comprising in combination, a frame, means for carrying record sheets interleaved with duplicating material upon said frame, a type frame mounted upon said frame, type characters movably carried upon said type frame, means for selecting predetermined type characters for a predetermined printing operation, means for disposing said selected type characters in printing position upon said frame with the type faces in con-

fronting relationship with the record sheets, means for locking said type frame in printing position above said record sheets with the selected type faces adjacent the record sheets, a pressure roll mounted upon said frame, means for moving said roll from its normal position trans-axially a limited distance for pressing said record sheets and duplicating material into printing contact with said selected type characters carried in the printing position to imprint duplicate data upon said record sheets, means for unlocking said type frame when said roll has reached its limiting position, and resilient means connected to said roll moving means and said frame to return said roll to its normal position.

19. A printing machine comprising in combination, a frame, means for carrying record sheets interleaved with duplicating material upon said frame, a type frame mounted upon said frame, type characters movably carried upon said type frame, means for selecting predetermined type characters for a predetermined printing operation, means for disposing said selected type characters in printing position upon said frame with the type faces in confronting relationship with the record sheets, means for locking said type frame in printing position above said record sheets with the selected type faces adjacent the record sheets, a pressure roll mounted upon said frame, means for moving said roll from its normal position trans-axially a limited distance for pressing said record sheets and duplicating material into printing contact with said selected type characters carried in the printing position to imprint duplicate data upon said record sheets, resilient means connected to said roll moving means to return said roll to its normal position, and means for moving the type frame to inoperative position with the selected type characters spaced a predetermined distance from the record sheet before said roll is returned to its normal position.

20. A printing machine comprising in combination, a frame, means for carrying record sheets interleaved with duplicating material upon said frame, a type frame swingably mounted at an end of said frame whereby said type frame may be swung upwardly from said frame, type characters movably carried upon said type frame, means for selecting predetermined type characters for a predetermined printing operation, means for disposing said selected type characters in printing position upon said type frame with the type faces of said selected type characters in confronting relationship with said record sheets, plate carrying means mounted upon said frame for carrying an impression plate in printing position upon said frame, means for locking said type frame in operative position above said record sheets with the selected type characters disposed adjacent said record sheets, and means for pressing said record sheets and duplicating material upwardly against said selected type characters and impression plate carried in the printing position to imprint duplicate data upon the record sheets, and means connecting said pressing means to said locking means for unlocking said type frame after said pressing means has caused the imprint of the duplicate data upon the record sheets.

21. A printing machine comprising in combination, a frame, means for carrying record sheets interleaved with duplicating material upon said frame, a type frame resiliently mounted

upon said frame, type members movably carried upon said type frame, means for selecting predetermined type members for a predetermined printing operation, means for disposing said selected type members in printing position upon said type frame with the type faces of said selected type members in confronting relationship with said record sheets, a latch for locking said type frame in operative position above said record sheets with said selected type faces adjacent said record sheets, and means for pressing said record sheets and duplicating material upwardly against said type members carried in printing position to imprint said record sheets with duplicate data, and means connecting said latch and said pressing means for tripping said

latch after said record sheets have been imprinted.
